UNITED STATES PATENT OFFICE.

RONALD ELISON CAMPBELL, OF COLUMBIA, SOUTH CAROLINA.

ADVERTISING DEVICE.

Application filed June 21, 1920; Serial No. 390,529.

To all whom it may concern:

Be it known that I, RONALD E. CAMPBELL, a citizen of the United States, and resident of Columbia, in the county of Richland, State of South Carolina, have invented certain new and useful Improvements in Advertising Devices, of which the following is a specification.

The object of this invention is to provide an advertising device particularly adapted for advertising soda fountain drinks. The invention relates particularly to the automaton type of advertising device which has heretofore been employed with well known effect in advertising various articles of commerce. Moving automatons attract the eye and attention of prospective purchasers in a manner which the ordinary stationary sign or display device of other character is incapable of doing and a more extensive use of automatons has heretofore not been attempted because of the expense involved in their installation and operation, and because of the large space which they occupy.

It is one of the principal objects of this invention to provide an automaton for advertising soda fountain drinks, or in fact drinks of any character, which is inexpensive to manufacture in the first instance; which is small in size and adapted to be installed in a small space in a store or a display window; which may be automatically and continuously operated by means of electric power; and which requires no connections other than a pair of electric wires for conducting the current from the electric mains to a motor.

One embodiment of the invention will be fully disclosed in the following description when taken in connection with the accompanying drawings, in which:

Figure 1 is a front elevation of the device;

Figure 2 is a similar view but showing the automaton in a different position and parts thereof being broken away to show the mechanism;

Figure 3 is a top view of the device;

Figure 4 is a section along the line 4—4 of Figure 3 to a larger scale part being broken away and showing certain of the parts in positions different from those which they occupy in Figure 3;

Figure 5 is a horizontal section through a portion of the pump; and

Figure 6 is a vertical section through the drinking glass held by the automaton.

Figure 7 is a plan view of a detail.

The advertising device comprises a flat wooden or cardboard figure, indicated at 10, which may be that of a man, as illustrated, or of a woman or child. To the right of the figure and indicated at 11 is a wood or cardboard structure representing the usual soda fountain, the rear edge of the member 11 being secured to a wall 12 in the rear of the Figure 10. Mechanism for operating the automaton is concealed behind this and behind the structure 11 representing the soda fountain.

In operation the concealed mechanism moves the pivot arm 13 of the automaton so that the glass 14 which it holds is carried from the soda dispensing spigot or faucet 15 to a position in front of the Figure 10 and directly below its mouth piece. In the last position mentioned the glass is emptied, the fluid therein passing upwardly through the glass tube 16 and through the mouth of the automaton into a system of piping by means of which it is conducted back to the glass, to be again consumed by the automaton. In other words, the automaton is caused to drink the same liquid repeatedly at regular intervals, although so far as the observer in front of the device can detect, the figure receives from the fountain a fresh glass of liquid each time the glass is placed beneath the spigot 15.

The mechanism for moving the arm in this manner and for causing the glass to be alternately filled and emptied will now be described. Leading rearwardly from the rubber mouth piece 17 of the automaton is a pipe 18 which opens into a cylinder 19 containing a sliding piston and constituting a pump and a pipe 21 connects the pump cylinder 19 and a storage reservoir 20 located behind the structure 11, and elevated above the level of the spigot 15. Nonreturn valves 22 and 23 respectively are located at the ends of the pipes 18 and 21 where they enter the cylinder 19, and the function of these valves is to insure that the liquid passes through the pump system in one direction only, which is of course, from the pump to the storage reservoir 20 as indicated by the arrows. The piston of the pump is connected by a rod 24 to the U shaped shaft 25, on one end of which is mounted the pulley 26, connected by means of a belt 27 to the small drive pulley of a small electric motor 28. Rotation of the

motor causes the pump to operate to withdraw, on its up stroke, the contents of the glass through the pipe 18 and to force the same, on its down stroke, through the pipe 21 into the storage reservoir 20. This pumping action although slow, takes place constantly, so that whenever the glass is brought into drinking position by the arm its liquid content is slowly drawn up the tube 16 and is forced immediately afterwards into the storage reservoir.

The liquid entering the storage reservoir is held therein until the glass 14 has been placed under the spigot 15, whereupon it is allowed to flow from the reservoir into the glass. The means for controlling the flow of liquid, whereby it is released only at the proper time, comprises a U-shaped tubular member 30, the ends of which are connected respectively, as illustrated, with the lower end of the reservoir 20 and with the spigot 15. This U-shaped tube is adapted to swing, in the operation of the device, from a vertical position as illustrated in full lines in Figure 4 to a substantially horizontal position, as illustrated in dotted lines in the same figure. As the top of the U-shaped member is above the level of the liquid surface when in its vertical position, no liquid can flow from the reservoir to the glass, but when the tube is in its inclined position its highest point is near the bottom of the cylinder 20 and, of course, a flow of liquid can take place from the cylinder to the glass. The inverted tube, therefore, in reality constitutes a valve, opening and closing the conduit through which the liquid must pass in flowing from the reservoir to the glass. The high point of the tube is supported by the end of a member 31 pivoted about the same axis as and movable with the tube at all times and having at its lower end a weight 32 which acts as a counterweight, exactly balancing the weight of the tube on the other side of the pivotal axis. The tube therefore, being exactly balanced by the weight 32, will remain in any angular position in which it is placed and will have no tendency to swing because of its own weight. Mechanism is provided for controlling the movements of the arm 13 and the operation of the tube 30 in accordance with the presence or absence of liquid in the storage reservoir. As clearly shown in Figures 2 and 4, the reservoir 20 contains a float 33 having an upwardly extending stem 34 to which an outwardly and downwardly extending arm 35, having a lateral projection 36 at its lower end, is secured. This projection 36 is adapted to contact with a lateral arm 37 fast on the rod 31 when the latter is in its inclined position and the float is descending. The weight of the float is sufficient to cause the rod 31 and U tube 30 to be returned to vertical position when the float

has descended to such an extent that the member 36 has engaged the arm 37 to force or cam the same out of its path. It is apparent therefore that as soon as the float 33 has descended a predetermined distance and a predetermined amount of fluid has passed from the reservoir 20 to the glass, the U shaped tube will be returned to vertical position, immediately cutting off the flow. This valve action occurs when the glass has been filled. When the reservoir 20 has been refilled by the pump, the float 33 is, of course, in its uppermost position and the tube 30 may be again rotated to inclined position when the glass is to be refilled.

For rotating the tube 30 to inclined position, a lever 38 pivotally mounted in the wall of structure 11 is provided, having a horizontal portion 38' outside of the wall and in the path of the glass 14, and a second horizontal portion 38" within the wall and lying in the path of the lower end of rod 31. When the glass is placed under the spigot it strikes the portion 38' of lever 38 and causes the rotation of the lever from the full line to the dotted line position (Figure 4), the portion 38" of the lever engaging and rotating the tube 30 into inclined position, as indicated in dotted lines in the same figure. Simultaneously, therefore, with the arrival of the glass 14 beneath the spigot the flow of fluid from the reservoir to the glass is commenced. As the float descends the member 36 engages the arm 37 to rotate the tube 30 to vertical position and to stop the flow of fluid at the same instant that the arm actuating mechanism is called into action to remove the glass, the lever 38 being simultaneously and automatically returned to its original position by the rod 31.

The arm 13 has at its inner or elbow end a worm wheel 39 meshing with a worm 40 mounted upon the end of a shaft 41 supported in the rear of the Figure 10 and having a pivoted connection to a shaft 42. This shaft 42 has mounted upon its inner end a friction wheel 43 which is adapted to engage either of friction wheels 44 or 45 mounted upon the shaft 25. The shaft 25 is, in the operation of the device, constantly rotated by the electric motor and it is obvious therefore that when the friction wheels 43 and 44 are together the shaft 41 and the worm 40 will be rotated to move the arm 13 in one direction and when the friction wheels 43 and 45 are together the worm will rotate the arm in the opposite direction. A spring 46 normally tends to force the wheel 43 against the wheel 45 and to maintain the arm 13 and the glass in drinking position.

A cord or wire 47 connects the shaft 42 to the lower end of the bell crank lever 48 pivotally mounted upon a fixed upright 49 adjacent the storage reservoir 20. The opposite end of the lever 48 extends over the stem

34 secured to the float. When the lever is in position as shown in Figure 4 the shaft 42 is drawn, against the pressure of the spring 46, so that the wheels 43 and 44 are in engagement and the arm 13 is in extended position. The lever 48 is held in such position until the float 29 has descended to its lower limit of travel by a pivoted supporting member 50 normally pressed by a leaf spring 51 10 toward the stem 34. When the float has approached its lower limit of travel the cam surface on the upper end of the stem 34 engages the lateral projecting shoulder 50' near the lower end of the pivot member 50 15 and the latter is forced to the left (Figure 2) against the action of the leaf spring 51, and the upper end of the member 50 disengages the lever 48 which falls until it again rests upon the upper end of the stem 34. When 20 the lever 48 falls the connecting cord 47 allows the spring 46 to shift the rod 42 so that the friction wheels 43 and 45 are in contact. Immediately, therefore, the arm 13 starts to return to drinking position. The float remains in its lowermost position until the liquid contained in the glass has been withdrawn and returned to the reservoir 20.

Inasmuch as by siphon action of the tube 30 the flow of liquid might continue until the 30 float chamber is drained, means is provided for automatically opening the tube to the air at its highest point when it returns to vertical position. This means comprises a valve 52 pivotally secured to tube 30 and having an aperture 53 and an arm 54, the valve being normally positioned as shown in full lines in Fig. 7 by a weak tension spring 55. As the tube 30 approaches vertical position the end of valve arm 54 strikes a projection 35 56 on wall 11 and the valve is rotated to the dotted line position (Fig. 7) in which position the aperture 53 is in register with an aperture 57 in tube 30 and air is admitted into the tube to break the suction. As the 40 tube 30 swings downwardly from vertical position, spring 55 causes valve 52 to rotate to close the aperture 57.

This cycle of operations will be continued as long as the motor is supplied with current. It is not necessary in this device for any connection to be made to a large liquid tank or to a water supply system inasmuch as the same liquid is used indefinitely. While the device is neat and attractive in appearance it is not expensive to manufacture, the parts are simple in construction, easily accessible, and the mechanism is easy to repair. Suitable advertising matter may be printed on the cardboard or wood figure or 55 other structure and the device placed in a comparatively small space in a store or display window.

It will be obvious that changes may be made in the form and arrangement of the 60 parts of the invention, which is not limited

to the embodiment described and illustrated.

Having thus described the invention what is claimed as new and desired to be secured by Letters Patent is:

1. In an advertising device, in combination, an open display vessel for a liquid, a power device, means including a pump, operable by said power device for emptying said vessel, and second means operable by said power device, for refilling the vessel after it has been emptied by the pump. 170

2. In an advertising device, an open display vessel for a liquid, means including a suction pump, for removing a liquid from said vessel, a power device for operating the pump, and second means operable by said power device for automatically refilling said vessel when it has been emptied by said first means. 180

3. In an advertising device, in combination, a display vessel for a liquid, a liquid storage reservoir, means including a pump for emptying liquid from said vessel and transferring it to said reservoir, a power device for operating said pump, and means, operable by said power device, for automatically refilling said vessel from the storage reservoir after it has been emptied. 190

4. In a device of the class described, a vessel for a liquid, a liquid storage reservoir, suction means for removing liquid from said vessel and transferring it to said reservoir, a power device for operating said suction means, means operable by said power device for refilling said vessel from the contents of the storage reservoir, and means for automatically operatively connecting said power device to said refilling means after said vessel has become emptied. 195

5. In a device of the class described, a vessel for a liquid, a liquid storage reservoir, pumping means for removing liquid from said vessel and transferring it to said reservoir, a power device for operating said pumping means, means operable by said power device for refilling said vessel from the contents of the storage reservoir, and means for automatically operatively connecting said power device to said refilling means, said connecting means being actuated when the level of the liquid in said storage reservoir exceeds a predetermined amount. 110

6. In a device of the class described, in combination, a vessel adapted to be moved from a filling to an emptying position, a reservoir, means for emptying said vessel of its contents when in said emptying position and delivering the same to the reservoir, means for filling said vessel from the reservoir when in filling position, and means to move said vessel from one position to the other. 120

7. In a device of the class described, in combination, a vessel adapted to be moved from a filling to an emptying position, a res- 130

ervoir, means for emptying said vessel of its contents when in said emptying position and delivering the same to the reservoir, means for filling said vessel from the reservoir when in filling position, and means to move said vessel along the arc of a circle from one position to the other.

8. In a device of the class described, in combination, a vessel adapted to be moved from a filling to an emptying position, a reservoir, means for emptying said vessel of its contents when in said emptying position and delivering the same to the reservoir, means for filling said vessel from the reservoir when in filling position, and means controlled by the height of the liquid level in said reservoir for moving said vessel from one position to the other.

9. In a device of the class described, in combination, a vessel adapted to be moved from a filling to an emptying position, a reservoir, means for emptying said vessel of its contents when in said emptying position and delivering the same to the reservoir, means for filling said vessel from the reservoir when in filling position, and means including a float in said reservoir and a lever operable thereby for moving said vessel from one position to the other.

10. In a device of the class described, in combination, a vessel adapted to be moved from a filling to an emptying position, a reservoir, means for emptying said vessel of

its contents when in said emptying position and delivering the same to the reservoir, means for filling said vessel from the reservoir when in filling position, and means, including friction reversing gearing, and a float in said reservoir and connected to said gearing, for moving said vessel from one position to the other.

11. In a device of the class described, in combination, a vessel adapted to be moved from a filling to an emptying position, a reservoir, means for emptying said vessel of its contents when in said emptying position and delivering the same to the reservoir, means including a pivoted U shaped conduit, for filling said vessel from the reservoir when in filling position, and means to move said vessel from one position to the other.

12. In a device of the class described, in combination, a vessel adapted to be moved from a filling to an emptying position, a reservoir, means for emptying said vessel of its contents when in said emptying position and delivering the same to the reservoir, means including a flow restraining device, and a lever for operating the same, for filling said vessel from the reservoir when in filling position, said lever being actuated by the vessel on reaching filling position, and means for moving said vessel from one position to the other.

In testimony whereof I affix my signature.
RONALD ELISON CAMPBELL.
